UNITED STATES PATENT OFFICE.

SWITS CONDÉ, OF OSWEGO, NEW YORK.

DESIGN FOR A KNIT FABRIC.

SPECIFICATION forming part of Design No. 12,319, dated June 21, 1881.

Application filed April 23, 1881. Term of patent 7 years.

To all whom it may concern:

Be it known that I, SWITS CONDÉ, of Oswego, in the county of Oswego, in the State of New York, have invented a new Design for 5 Knit Shirts and Drawers, of which the following, taken in connection with the accompanying drawings, is a full, clear, and exact description.

This design consists in shirts and drawers 10 knitted of two or more differently-colored yarns in such a manner as to produce dark and light mottled stripes arranged alternately and horizontally in relation to the garment.

In the annexed drawings, Figure 1 shows 15 my design applied to the body of a knit shirt, and Fig. 2 is an enlarged view of a section of the fabric of which said shirt is composed.

a and *b* represent dark and light mottled stripes respectively, which, by peculiar mechanism connected with the knitting-machine, 20 unnecessary to be here described, are wrought of two or more differently-colored yarns made

to predominate one over the other at the surface of the fabric, and alternating after a definite number of revolutions of the machine, thus 25 causing said stripes to run horizontally or transversely in relation to the garment, as illustrated in Fig. 1 of the drawings.

What I claim is—

The design for a knit fabric to be used for 30 shirts and drawers, consisting of dark and light mottled stripes arranged alternately and horizontally in relation to the garment, substantially as described and shown.

In testimony whereof I have hereunto signed 35 my name and affixed my seal, in the presence of two attesting witnesses, at Oswego, in the county of Oswego, in the State of New York, this 19th day of April, 1881.

SWITS CONDÉ. [L. S.]

Witnesses:

FRED. L. CONDÉ,
EDWD. MAXWELL.
